US0D1039826S

(12) **United States Design Patent** (10) **Patent No.:** **US D1,039,826 S**
(45) **Date of Patent:** **** Aug. 27, 2024**

(54) **GARMENT CARE DEVICE**

(71) Applicants: **GUANGZHOU SHIYUAN ELECTRONICS CO., LTD.**
Guangdong (CN); **GUANGZHOU YIJIA SMART TECHNOLOGY CO., LTD.**, Guangdong (CN)

(72) Inventor: **Xiangzhong Bai**, Guangdong (CN)

(**) Term: **15 Years**

(21) Appl. No.: **29/764,285**

(22) Filed: **Dec. 29, 2020**

(30) **Foreign Application Priority Data**

Jun. 29, 2020 (CN) 202030338577.X

(74) *Attorney, Agent, or Firm* — Zhong Law, LLC

(57) **CLAIM**

The ornamental design for a garment care device, as shown and described.

DESCRIPTION

FIG. 1 is a front view of a garment care device showing my new design;

FIG. 2 is a rear view thereof;

FIG. 3 is a left side view thereof;

FIG. 4 is a right side view thereof;

FIG. 5 is an enlarged top view thereof;

FIG. 6 is an enlarged bottom view thereof;

FIG. 7 is a front perspective view of the garment care device; and,

FIG. 8 is a rear perspective view thereof.

The broken lines shown in the figures are for the purpose of illustrating portions of the garment care device and form no part of the claimed design.

1 Claim, 8 Drawing Sheets
